(Cl. D44—22)

To all whom it may concern:

Be it known that we, Harry J. Keener and George C. Gartner, both citizens of the United States, residing, respectively, at Minerva, Stark County, Ohio, and Salem, Columbiana County, Ohio, have invented a new, original, and ornamental Design for a Condiment Holder or Similar Article, of which the following is a specification, reference being had to the accompanying drawings, forming part thereof.

Fig. 2 is a side elevational view thereof;

Fig. 3 is a rear elevational view thereof; and

Fig. 4 is an opposite side elevational view thereof.

We claim:

The ornamental design for a condiment holder or similar article, substantially as shown.

HARRY J. KEENER,
GEORGE C. GARTNER.
